(57) **CLAIM**

The ornamental design for an earpiece cap, as shown and described.

DESCRIPTION

FIG. 1 is a front perspective view of an earpiece cap showing our new design, illustrated in an open position, and attached to an example filter;

FIG. 2 is a rear perspective view thereof;

FIG. 3 is a front side elevational view thereof;

FIG. 4 is a rear side elevational view thereof;

FIG. 5 is a right side elevational view thereof;

FIG. 6 is a left side elevational view thereof;

FIG. 7 is a top plan view thereof; and

FIG. 8 is a bottom plan view thereof.

FIG. 9 is a rear perspective view of the earpiece cap, illustrated in the open position, and attached to an example earpiece; and

FIG. 10 is a right side elevational view thereof.

FIG. 11 is a front perspective view of the earpiece cap, illustrated in a closed position, and attached to the example filter;

FIG. 12 is a rear perspective view thereof;

FIG. 13 is a front side elevational view thereof;

FIG. 14 is a rear side elevational view thereof;

FIG. 15 is a right side elevational view thereof;

FIG. 16 is a left side elevational view thereof;

FIG. 17 is a top plan view thereof; and

FIG. 18 is a bottom plan view thereof.

FIG. 19 is a rear perspective view of the earpiece cap, illustrated in the closed position, and attached to the example earpiece; and,

FIG. 20 is a right side elevational view thereof.

The broken lines in the drawings illustrate environmental features and form no part of the claimed design.

1 Claim, 20 Drawing Sheets
